UNITED STATES PATENT OFFICE.

JOHN H. WAITE, OF BROCKTON, MASSACHUSETTS.

SHANK-PIECE FOR BOOTS AND SHOES.

1,068,089.

Specification of Letters Patent.

Patented July 22, 1913.

Application filed February 17, 1912. Serial No. 673,818.

To all whom it may concern:

Be it known that I, JOHN H. WAITE, a citizen of the United States, residing at Brockton, in the county of Plymouth and 5 State of Massachusetts, have invented a new and useful Shank-Piece for Boots and Shoes, of which the following is a specification.

This invention relates to that class of 10 boots and shoes in which special provision is made for supporting the arch, and the principal objects thereof are to provide a boot or shoe with a practicable and efficient shank piece of a novel and economical form 15 which while having all the strength of an ordinary shank piece will be more flexible, and therefore, more comfortable to the wearer.

The invention also has for one of its objects 20 the provision of these devices of such a form and nature that they will tend to prevent the falling of the arch in a normal foot and will also efficiently support an arch that has already fallen.

25 The principal cause for the development of fallen arches is the cheapening of the shoe and particularly of the shank thereof. On account of the construction of this part with the main supporting element concealed, it can be cheapened very easily without detection and this has been done to such 30 a degree within recent years that even the better classes of shoes have been materially weakened. This invention provides for 35 strengthening this part of the shoe without materially increasing the cost. It may be remarked also that another cause of this difficulty is the almost universal demand for light hand sewed or Goodyear shoes. By 40 this invention the advantages thereof are secured without danger of weakening the arches, and in fact with an accompanying means for supporting them.

45 Reference is to be had to the accompanying drawings, in which—

Figure 1 is a side elevation of a portion of a shoe constructed in accordance with this invention; Fig. 2 is a bottom plan view thereof with parts removed to show interior 50 construction; Fig. 3 is a transverse sectional view on the line 3—3 of Fig. 2, and Fig. 4 is a side view of the arch reinforcing piece.

The invention is shown in simple form, and as the order of steps in manufacture is 55 substantially the same as that commonly em-

ployed for machine made shoes, it need not be described in detail.

The shoe is shown as having a vamp 8, insole 9, counter 10, welt 11, and outsole 12. The reinforcing piece 13 consists of a single 60 piece of leather skived around its edges and provided with one straight edge 14 and a continuously curved edge 15 opposite. This is placed in the shoe after the counter is in, coming between the lining and the upper on 65 the inner side of the shank. Preferably it just laps over the inner end of the counter. The straight edge 14 is drawn in and lasted, temporarily tacked to the last. Then it is firmly secured in position by sewing through 70 the channel 16 in the insole to unite the upper, lining, welt, and reinforcement to the insole by a row of stitches 17. It will be seen that the straight edge permits the reinforcement to be drawn over the edge of 75 the insole and to be secured thereto conveniently in the manner just described. At the same time it does not involve the making of a different shape at this point from that which ordinarily prevails as is the case with 80 integral reinforcements heretofore proposed. And it can be made of a different material from the insole and preferably is made of stiffer firmer material like the counter. Although it materially strengthens the 85 shank at this point and effectively supports the instep it still is capable of yielding sufficiently to make a comfortable shoe and it is particularly comfortable on account of the fact that it can be made to fit just as 90 closely to the foot as does any shoe that is machine made. It will be seen also that the shape of the reinforcement is such that it can be made with very little waste and even from small pieces of leather, and also it can 95 be made of different kinds of leather according to the amount of rigidity or flexibility desired. As a particular addition to this feature, attention is called to the shank piece which is shown as composed of two pieces 100

of spring steel 20 and 21. The piece 20 is secured to the sole fixedly at a point substantially as far forward as the front end of the reinforcing strip and the piece 21 is secured at the opposite end at a point near 105 the adjacent end of the reinforcing strip. The piece 20 is provided with two projections 22 separated from each other so as to constitute a bifurcated structure extending rearward so as just to overlap the front edge 110

of the piece 21. The piece 21 has a single projection 23 extending forwardly between the projections 22 so as to just overlap the edge of the piece 20. It will be understood 5 that the three ends of these projections are on the under sides of the two pieces 20 and 21 coming into contact therewith so as to exert pressure upon them and to receive pressure from them while the shoe is being 10 worn. This shank piece is an important feature, as it has great flexibility, but yet is very strong. It is so shaped that practically no metal is lost in stamping out the two members that compose it and, taken alto- 15 gether, it is almost co-extensive in length with the reinforcing piece. Their adjacent edges extend along substantially parallel with each other and very close together throughout their lengths. In this way this 20 part of the shoe is made flexible to a certain extent and yet it is so strong as to hold up the arch effectively. It will be seen therefore that these two features mutually coöperate to produce the desired result, and that 25 they are so located with respect to each other that each assists the other in doing so.

Although I have illustrated and described a preferred embodiment of the invention and shown it as applied to a particular type 30 of shoe, it is to be understood that I am aware that the invention can be carried out in other forms and can be applied to many other types of boots and shoes without departing from the scope of the invention as

expressed in the claims. Therefore I do not 35 wish to be limited to all the details herein shown and described, but

What I do claim is:—

1. As an article of manufacture, a shank piece for boots and shoes consisting of two 40 steel members, one member adapted to be secured firmly to the insole at one end and having two separated projections extending therefrom in the same plane and free at their ends, the other fixed at the opposite 45 end and having a single projection extending freely therefrom between the two projections on the other member.

2. As an article of manufacture, a shank piece for boots and shoes consisting of two 50 members, one member adapted to be secured firmly to the insole at one end and having two separated projections extending therefrom and free at their ends, the other adapted to be fixed at the opposite end and having a projection extending freely therefrom between the two projections on the other member, the two projections extending toward the heel and the other projection away from the heel, and each projection 55 overlapping the other member near its end.

In testimony whereof I have hereunto set my hand in the presence of two subscribing witnesses.

JOHN H. WAITE.
